[57] CLAIM

The ornamental design for an upper torso protector for motorcyclists and the like, as shown and described.

DESCRIPTION

FIG. 1 is a front elevational view of an upper torso protector for motorcyclists and the like showing my new design;

FIG. 2 is a rear elevational view thereof;

FIG. 3 is a right side elevational view, the left side being a mirror image thereof;

FIG. 4 is a top plan view thereof; and

FIG. 5 is a bottom view thereof.
